(57) **CLAIM**

The ornamental design for an electric connector, as shown and described.

DESCRIPTION

FIG. 1 is a front perspective view of the first embodiment of the electric connector;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and

FIG. 8 is a bottom view thereof.

FIG. 9 is a front perspective view of the second embodiment of the electric connector;

FIG. 10 is a rear perspective view thereof;

FIG. 11 is a front view thereof;

FIG. 12 is a rear view thereof;

FIG. 13 is a left side view thereof;

FIG. 14 is a right side view thereof;

FIG. 15 is a top view thereof; and,

FIG. 16 is a bottom view thereof.

(Continued)

The broken lines in the figure drawings are included to show the portions of the electric connector that form no part of the claimed design.
